UNITED STATES PATENT OFFICE.

FREDERICK FARRAR, OF BOSTON, MASSACHUSETTS.

WRENCH.

SPECIFICATION forming part of Letters Patent No. 331,627, dated December 1, 1885.

Application filed March 9, 1885. Serial No. 158,180. (No model.)

To all whom it may concern:

Be it known that I, FREDERICK FARRAR, of Boston, county of Suffolk, State of Massachusetts, have invented an Improvement in 5 Wrenches, of which the following description, in connection with the accompanying drawings, is a specification, like letters on the drawings representing like parts.

This invention in wrenches is an improvement upon that class of wrench wherein the jaws are made movable on a head-block having an attached ratchet-toothed segment pivoted upon a slotted shank portion, my invention having for its object to simplify and 15 improve the construction of wrenches of the class referred to, and to make the same capable of resisting much greater strain than heretofore.

To this end the invention consists in the 20 combination and arrangement of parts, as hereinafter described, and more particularly set forth in the claim.

Figure 1 shows in elevation a wrench embodying my invention, the shank portion being broken away to more fully show the operating parts; Fig. 2, an end view of the head-block and jaws; Fig. 3, a cross-section of the head-block, taken on the dotted line x_1x_1 , Fig. 5; Fig. 4, a cross-section of a jaw, taken on 25 dotted line x_2x_2 , Fig. 2; and Fig. 5, a longitudinal section of the head-block.

The shank portion A' , having the handle A , is slotted at its end to receive the ratchet-toothed segment a , forming, preferably, an 35 integral part of the head-block c , the pin a' serving as a pivot for the said head. The slot in the shank A' also receives a pawl, b , pivoted at b^3 , which co-operates with the ratchet-toothed segment a to hold the same in any 40 desired position. The pawl b is normally held in engagement with the ratchet-toothed segment a by the spring b^2 acting on the thumb-piece b' , the depression of the latter disengaging the pawl b from the said ratchet-toothed 45 segment. The head-block c , preferably integral with the ratchet-toothed segment, is recessed or grooved, as at c' , parallel with and at each side of the screw or bolt d , to form guideways for the movable jaws $2, 3$, which 50 are provided with corresponding guiding-projections c^2, c^3 . The head-block c is recessed or

bored longitudinally, as shown in Fig. 5, the portion e serving as a bearing for the right-and-left-threaded bolt or screw d , which is passed therethrough, and the portion e' of the 55 recess being of larger diameter and cut away, as shown in Fig. 2, leaving open slots or guideways for the bridge-pieces f , which extend across and unite the guide portions of each of the movable jaws. The bridge-pieces 60 f of the movable jaws are oppositely screw-threaded internally, as at 4, to engage the right-and-left-threaded bolt d , rotation of which moves the jaws on the head-block.

The bolt d is turned by a suitable milled 65 thumb-nut, d' , secured thereto, preferably a nut at each end of the bolt. Upon turning the bolt d in one direction the movable jaws 2, 3 may be made to approach each other until their faces meet, the bridge-pieces f following 70 in the slots. The guideways c' are at opposite sides of and parallel with the bolt d , so that no strain comes upon the bolt d to injure the wrench; but, on the contrary, the entire 75 strain of the jaws comes upon the guide portions of the head-block, which are engaged by the guide portions c^2, c^3 , as shown, the head-block, not the bolt d , resisting the strain exerted upon the jaws. This forms the most 80 important feature of my invention.

The head-block supporting the jaws being pivoted and controlled by a ratchet and pawl, any inclination desired may be given to the 85 jaws with relation to the shank portion.

I am aware that wrenches have been made 90 consisting of a guide-block having an integral ratchet-toothed segment pivoted to the shank portion of the wrench, and that a head-block has been provided with a single guide, upon which the movable jaws were made to slide 95 by means of a right-and-left-threaded screw or bolt; but such construction I do not herein claim, as it is obvious that the entire strain comes upon the bolt.

I claim—

A wrench comprising the head-block c , pivoted to the handled shank and provided with the ratchet-toothed segment and pawl co-operating therewith, the double-acting screw d , arranged in said head-block, and the guides c' 100 c^2, c^3 on opposite faces of the head-block and both sides of the screw, combined with the jaws 2

and 3, having the guiding-projections c^2 c^2 ,
engaging said guides $c' c'$, and the threaded
bridges f , to receive the screw to cause said
jaws to move in parallelism and without strain
5 and tendency to bind upon the screw, sub-
stantially as shown and described.

In testimony whereof I have signed my name

to this specification in the presence of two sub-
scribing witnesses.

FREDK. FARRAR.
